UNITED STATES PATENT OFFICE.

ELMER E. SHAFFER, OF TULSA, OKLAHOMA.

METHOD AND APPARATUS FOR DRILLING OIL AND GAS WELLS.

1,166,011.

Specification of Letters Patent.

Patented Dec. 28, 1915.

Application filed February 15, 1915. Serial No. 8,329.

To all whom it may concern:

Be it known that I, ELMER E. SHAFFER, a citizen of the United States, residing at Tulsa, in the county of Tulsa and State of 5 Oklahoma, have invented new and useful Improvements in Methods and Apparatus for Drilling Oil and Gas Wells, of which the following is a specification.

This invention relates to an improved 10 method and apparatus for drilling oil and gas wells which I have termed the "standard rotary drilling outfit" in that it combines the desirable features of the so-called "standard" and "rotary" outfits, it being well known that for drilling through 15 mud and loose sands or other soft formations the rotary method is superior to the standard or reciprocating, while for drilling hard rock formations the standard or 20 concussion outfit is more rapid in action than the rotary. The apparatus is especially desirable for drilling in coast countries and other localities where the formations are largely soft and intermingled with 25 shale and lime shells. Ordinarily the casing consists of strings or sections of pipe gradually decreasing in diameter say from 30 a maximum of about fifteen and one-half inches to a minimum of four and one-half inches. This construction requires separate sets of different sized drilling tools, one for each size of pipe, rendering the equipment correspondingly expensive. The stems for rotary tools require a large quantity of 35 pipe which constitutes a material part of the cost of the outfit, while the pulling out of the stem to change the bits or tools involves a considerable item of time and labor.

One of the objects of my invention is 40 the provision of a relatively inexpensive combination outfit of this kind which can be readily converted from the standard to the rotary form or vice versa, in order to utilize the recognized advantages of each, 45 according to the nature of the formations.

A further object is to so construct the casing that but a single size or set of drilling tools is required, and further to utilize the casing of the standard outfit as a driver or 50 rotating means for the rotary drilling tools, thus dispensing with the usual separate drill stem and saving its cost and the time and labor required to withdraw and replace it in changing the tools.

55 Further objects are to improve the ap-

paratus in various other respects as will hereinafter appear.

In the accompanying drawings: Figure 1 is a sectional elevation of the improved apparatus assembled as a rotary outfit. Fig. 60 2 is an enlarged sectional elevation of the mechanism for rotating the casing, the flush-head and intermediate parts. Fig. 3 is a vertical section, on an enlarged scale, of the flush-head. Fig. 4 is a horizontal section 65 on lines 4—4, Fig. 2. Fig. 5 is a similar section on line 5—5, Fig. 2. Fig. 6 is an enlarged sectional elevation of the rotary casing, the tool-socket and the means for coupling the latter to the pipe. Fig. 7 is a sectional elevation of said tool socket on a still 70 larger scale, showing the position of its movable parts while the socket is being lowered through the rotary casing. Fig. 8 is a similar view showing the tool socket lowered 75 and coupled to the casing. Fig. 9 is a vertical section at right angles to Fig. 8. Figs. 10 and 11 are horizontal sections on the correspondingly-numbered lines in Fig. 8. Fig. 12 is an enlarged vertical section of 80 the coupling sleeve with which the coupling members of the tool socket coöperate. Fig. 13 is a perspective view of one of the clutch-blocks of the tool socket. Fig. 14 is a similar view of one of the stop-dogs of said 85 socket.

Similar characters of reference indicate corresponding parts throughout the several views.

1 indicates the usual derrick; 2 its main 90 or floor-sills; 3 the walking beam; 4 the pitman shown detached from the crank shaft which latter carries the band wheel 5; 6 the bull wheel; 7 the sand reel and 8 the usual pumps. These several parts may 95 be of any suitable or well known construction.

9 indicates a horizontal table-gear such as ordinarily employed in rotary drilling outfits, the same being supported by a roller 100 bearing 10 mounted on sills 11 or other supports, preferably arranged below the main derrick sills 2. This table-gear is driven by the pinion 12, the shaft 13 of which may be connected with the driving shaft 14 by 105 the usual clutch 15. Mounted upon this table-gear are the customary clutch wheels or rollers 16 adapted to grip the part to be rotated which in the present case is the well casing 17, so as to compel said casing to 110

rotate with the table-gear 9 and at the same time allow the casing to move up or down through it. The shafts of these rollers are mounted in movable bearings 18 which are adjusted by the usual screws 19 to cause the rollers to grip said pipe.

20 indicates the usual drive-pipe of the well which is sunk to a suitable depth in any well known manner. Through this casing 10 is lowered the well-casing 17 which is sufficiently smaller in diameter than the casing 20 to permit the slush or mud to ascend between these pipes into the customary slush-discharge pipe 21. For example, the drive-pipe may be twelve and one-half inches and the casing eight inches in diameter. This casing is adapted to extend from the top to the bottom of the well and to serve not only as an oil discharge pipe but also as a 15 tool or drill-stem which is rotated by the table-gear 9 and in turn rotates the underreamer 22 or other rotary tools, such as are commonly used for drilling through sand or mud formations and ordinary rock formations, such tools being carried by a tool-socket or head adapted to be coupled to the 25 rotary casing by suitable coupling or clutch means, thus dispensing with the usual separate tool-stems heretofore employed in addition to the non-rotary casing. These coupling devices will be hereinafter more fully described.

The casing 17 consists of sections of suitable length connected by couplings of any 30 suitable construction, the coupling 23 shown in the drawings being the lowermost one of the casing. Instead of being composed of strings of different-sized pipe, as heretofore, the entire casing preferably consists of pipe 35 lengths of uniform size, say eight-inch pipe. At its lower end the rotary casing is adapted to carry a shoe 24 or other suitable drilling tool which bores the well-hole in advance of the casing and is rotated by its rigid connection therewith. This shoe may be of any suitable construction. That shown in the drawings forms the subject of a separate application about to be filed by me and comprises an upwardly-tapering perforated tube 40 screwed upon the lower end of the casing and provided with spiral rows of openings 45 extending from the lower edge nearly to the top of the tube. The openings of the lowermost rows are partial or mutilated 50 openings, so that their lateral portions form the cutting edges of the shoe. By this construction before the lowermost openings are wholly worn away, those of the succeeding row come into action and in turn form the 55 cutting edge, thus rendering the tool self-sharpening.

The upper portion of the casing 17 extends centrally through a vertically-movable spider or plate 26 which in the preferred 60 construction shown in the drawings, is car-

ried by the plungers 27 of hydraulic jacks 28, whereby the spider and the casing 17 suspended therefrom may be raised or lowered by forcing liquid into said barrels or allowing it to exhaust therefrom. For this purpose, the lower ends of the several barrels of the jacks may be connected with a hollow supporting base 29 to which fluid under the required high pressure is supplied by a hydraulic pump, not shown, through a 75 pipe 29^a, which may also serve as a drain or discharge pipe by the use of suitable valves. These jacks are preferably arranged in a pit 30 in order to bring the spider 26 about on a level with the derrick floor and the table gear 9 below it. Mounted upon said spider is a suitable anti-friction bearing which in the construction shown consists of a lower non-rotary ring or plate 31 and an upper rotary ring or plate 32, these rings containing races 80 in which conical rollers 33 run. This rotary ring contains a divided plug or bushing 34 through which the upper portion of the casing passes. Removably attached to the screw threaded upper end of the casing is a flush 85 head 35 of any suitable construction and interposed between this flush-head and the plug 34 is an elevator 36 of any appropriate construction. The coupling-collar 37 between the flush-head and the upper end of the casing 90 forms a stop which rests upon the elevator 36, which in turn is supported by the upper ring 32 of the cone-bearing, whereby the flush-head and the elevator are free to rotate with the casing relatively to the spider 26. 100 In the preferred construction shown in the drawings, Figs. 2 and 3, the flush-head comprises a lower stuffing box 38, an upper stuffing box 39 and an externally-threaded tube or sleeve 40 connecting said boxes. 105 Passing axially through these stuffing boxes is an inlet or flushing pipe 41 which extends into the upper end of the casing while its projecting upper end has an elbow 42 to which is attached the hose 43 or other conduit connected with the slush-pumps 8. This construction while forming a tight joint permits the flush-head 35 to rotate on the stationary inlet pipe 41. To prevent longitudinal displacement of this pipe in 110 the flush-head, it is provided within the cap 44 of the head with a collar 45 which is interposed between the upper end of the stuffing box 39 and the lower ring 46 of an anti-friction bearing, preferably of the ball type seated in the upper end of said cap, as shown in Fig. 3. This ball bearing receives the upward thrust against the pipe 41 due to the back pressure of the water therein, reducing friction between the rotary flush head and said pipe and preventing the latter 115 from turning with the head.

In the preferred construction of the elevator 36 shown in the drawings, the same is divided vertically into two sections hinged 120

together at their rear ends by a vertical pin 47 and detachably connected at their opposite ends by a latch or locking device 49 of any suitable or well known construction. 5 Pivoted to opposite sides of the elevator are the customary links 50 adapted to engage the usual derrick-tackle for pulling up the casing 17. To permit the removal of these links so as to be out of the way when not 10 in use, the elevator is provided with downwardly-opening seats or sockets 51 for the inner cross bars of the links, which sockets are normally closed by caps 52 held in place by bolts 53 or other suitable means to permit 15 the ready removal of the caps and links.

54 indicates a tool socket or head which is adapted to be lowered through the casing 17, nearly to its lower end, and to the lower end of which the under-reamer 22 or other 20 rotary tool is attached by any suitable means, the preferred means being a tube 55 connected with the under-reamer and the tool socket by couplings 56. At its upper end this tool socket is provided with a comparatively 25 short upwardly-extending shank or stem 57 having a head 58 adapted to be engaged by a horn-socket or other suitable tool by which it is lowered into the casing and withdrawn therefrom. A tool of this character is shown and described in a separate application for patent about to be filed by me.

Located in recesses in opposite sides of the tool-socket, near its lower end, are a pair of 35 stop-dogs or pawls 59 pivoted between their ends on horizontal pins 60 carried by the socket. The lower ends of these dogs are normally retracted to the position shown in Fig. 7 in which they permit the tool socket 40 to be freely lowered through the casing 17. When the lower ends of the dogs are swung outward, as shown in Figs. 6 and 8, they are adapted to engage with and be stopped by a toothed ring or shoulder 61 arranged with- 45 in the casing at a suitable distance from its lower end. This ring preferably forms part of the lowermost coupling 23 of the casing, as best shown in Figs. 8, 9 and 12. When thus expanded, these dogs by striking the 50 toothed-ring 61 arrest the descending tool socket at the desired depth. Extending across the upper ends of the dogs is a vertically-sliding key or cam-bar 63 guided in vertical slots 64 in the tool socket and provided with beveled faces 65 which respectively engage the outer sides of the dogs, so that when the cam-bar is depressed from the position shown in Fig. 7 to that shown in Fig. 8, it forces the upper arms of the dogs inwardly, thereby throwing their lower 55 arms outwardly ready to engage the toothed stop-ring 61. This cam-bar is constantly drawn downward by a spring 66 bearing at its upper end against an abutment 67 of the tool socket and at its lower end against a

tube or sleeve 68. This tube slides in a longitudinal chamber 69 in the lower portion of the tool-socket and bears at its lower end against a nut or projection 70 on a rod or bolt 71 which slides in the abutment 67 and 70 is provided in its upper portion with a longitudinal slot 72 through which the cam-bar 63 passes. This spring thus tends constantly to depress the cam-bar 63 through the medium of the tube 68 and the bolt 71. 75

The large upper portion of the tool socket is hollow to receive a vertically-movable wedge 73 to which the lower end of the stem 57 is secured. This stem slides in an opening formed centrally in a cap 74 applied to 80 the upper end of the tool-socket. The wedge 73 is interposed between a pair of radially-sliding clutch-blocks or members 75 which are guided in a slot 76 formed in the adjacent portion of the tool head. These clutch 85 blocks are preferably interlocked with said wedge in such manner that when the wedge is lowered relatively to the blocks they are forced outwardly while when the wedge is raised, the blocks are retracted. For this 90 purpose, the wedge is preferably provided on opposite sides with undercut tenons 77 which engage corresponding grooves 78 in the backs of the blocks, as shown in Fig. 10. To center the wedge in the tool-socket during 95 its movements, the same is provided in its sides with vertical grooves 79 which receive horizontal guide pins 80 carried by the body of the tool socket, as shown in Figs. 9 and 10. The clutch blocks are provided in 100 their outer faces with vertical ribs, teeth or flutes 81 preferably of V-shaped cross section, as shown in Figs. 10 and 13. These ribs are adapted to interlock with an annular series of corresponding ribs or teeth 82 105 arranged lengthwise on the inner side of the coupling section 23 of the casing, whereby the rotary movement of the casing is transmitted to the tool socket and the tool carried by it, the coöperating ribs of the casing and the blocks 75 thus practically constituting clutch members which, when interlocked, drive the tool socket from the rotary pipe and when disengaged allow the casing to 110 turn independently of the tool socket. As shown in Figs. 8 and 9, the portion of the coupling section 23 located between its ribs 82 and stop-teeth 61, is of somewhat greater internal diameter than the portions thereof carrying said ribs and teeth, the last-named portions being substantially of the same internal diameter as the pipe-sections of the casing 17. By this construction, the 115 dogs 59 are held in their retracted position by contact with the interior of the casing during the lowering of the tool socket and remain in that position until they pass below the ribs 82, when, owing to the enlarged diameter of the coupling section 23, 120 they are allowed to swing out under the ten-

130

130

sion of the spring 66 exerted through the cam-bar 63. By the continued lowering of the tool-socket, the expanded dogs encounter the toothed ring 61 which arrests the socket, 5 as hereinbefore described. While thus lowering the tool socket, the wedge 73 is withdrawn to the position shown in Fig. 7, in which its large end bears against the cap 74 of the tool socket. The tool socket is therefore suspended from this wedge and the 10 stem 57 during this lowering operation and the parts remain in this position until the expanded dogs are arrested by the toothed ring 61, whereupon the wedge continues to 15 descend by gravity independently of the arrested socket, thereby spreading the clutch blocks 75 into engagement with the teeth 82 and coupling the tool socket to the rotary casing 17, as before described. The stop 20 ring 61 is located at the proper distance below the clutch ribs 82 to arrest the tool-socket when the clutch blocks arrive opposite the ribs. The teeth of this stop-ring are arranged at its upper edge and are V-shaped, 25 and the stop-dogs are provided at their lower ends with corresponding teeth 59^a adapted to engage those of the ring. The teeth of the ring are so arranged relative to the coupling ribs 82 that in case the ribs of 30 the clutch blocks, in lowering the tool socket, fail to mesh with the ribs 82 the toothed dogs upon engaging with the teeth of the stop ring 61 will be deflected laterally by the inclined sides of the teeth, thereby rotating 35 the tool-socket sufficiently to bring said ribs into proper mesh. The ribs of the clutch blocks are thus prevented from mounting those of the rotary casing, insuring the proper coupling of the tool socket to the 40 casing. It is obvious, however, that so far as the stop function of the ring 61 is concerned, its teeth are not necessary. By employing stop-devices of this kind which are separate from and independent of the clutch 45 blocks 75, the stop devices carry the weight of the tool socket when the latter is lowered to the proper depth to engage the ribs 82 of the casing, thus relieving the clutch blocks from such weight, leaving them free to slide 50 in and out with comparatively little friction and rendering them reliable in action. Upon elevating the tool socket through the casing 17, the dogs on coming in contact with the ribs 82 of the coupling section are forced 55 inward to their retracted position, permitting the tool to be withdrawn from the casing without restraint. By this inward movement of the lower arms of the dogs their upper ends force the cam-bar 63 by 60 bearing against its beveled faces 65, thereby pulling the bolt 71 and the tube 68 upward and again tensioning the spring 66. As shown, the coupling sleeve 23 is preferably located some distance above or remote from 65 the shoe or lower end of the casing. By this

arrangement, the coupling devices which connect the tool-socket to the rotary casing are a sufficient distance from the shoe and bit to avoid the liability of their becoming clogged with mud, insuring the reliable action of the coupling devices at all times. 70

As shown in Figs. 7, 8 and 9, the tool socket is provided near its lower end with suitable packing 83 which bears against the surrounding well-casing to check the descent of 75 the flushing water between it and the tool.

85 indicates one or more descending water passages extending inwardly from the periphery of the tool-socket at a point above the packing 83 and thence downwardly 80 through the central portion of the socket to the tube 55 for supplying water to the under-reamer bit.

In order to allow the water to pass up 85 through the tool-socket and permit it to be lowered quickly, the socket is provided with a number of longitudinal relief passages 84 extending from its bottom to a point above the packing 83. Upwardly-opening check valves 86 are applied to the upper ends of 90 these relief passages to prevent the water from descending through them instead of through the bit-supplying passages 85.

The operation of the apparatus is as follows: The drive pipe 20 is sunk in the usual manner. When the apparatus is to be used as a rotary outfit, its parts are assembled as shown in the drawings, the flush head 35 being connected to the upper end of the casing 17 and the latter clutched to the rotary head or table gear 9, so as to be rotated thereby, as hereinbefore described. The rotary shoe 24 of the casing drills a hole larger than the external diameter of the casing, leaving a 100 passage around the casing through which the drillings are flushed into the discharge pipe 21 by the stream of water forced through the casing by the pumps. As the drilling proceeds, the casing which is carried by the hydraulic jacks 28 is fed downward gradually by draining the water from the jacks. Any other rotary tools to be used, such as the under-reamer 22, are attached to the tool-socket 54 which is lowered through 105 the casing by a cable, cable tools and a suitable horn socket or similar implement, and automatically coupled to the rotary casing, as hereinbefore described, to drive the same from the casing, instead of by the separate 110 drill or auger stem ordinarily employed. By the same horn socket, this rotary tool may be uncoupled from the casing and withdrawn therefrom and another rotary tool substituted therefor, as required. New lengths of 115 casing or pipe are added by first removing the flush-head 35 from the stop-collar 37 and attaching said head by a similar stop collar to a new length of pipe. A second elevator 120 the same as the elevator 36 is then put over the stop collar of the new pipe-length and 125 130 135 140 145 150 155 160 165 170 175 180

the flush head is raised with derrick tackle attached to said second elevator. The added length of pipe is next screwed into the stop-collar 37 of the casing 17 and the latter is 5 raised by the derrick tackle sufficiently to permit the removal of the first elevator 36, the casing 17 being suspended by said second elevator attached to the derrick-tackle. By means of the hydraulic jacks, the spider 26 10 and the swivel or bearing composed of the parts 31, 32 and 33 are then raised to meet said second elevator, which together with the casing are meanwhile sustained by the derrick tackle. The derrick tackle is then 15 detached and the casing is again supported by the jacks.

In using the apparatus with standard or concussion drilling tools, the flush-head 35 20 is removed from the casing, the under-reamer or other rotary tool is withdrawn by means of said cable, cable tools and horn socket, a standard bit or tool is substituted for said horn socket and said cable tools and bit are then lowered through the casing and 25 actuated in the customary manner, the bit drilling some distance in advance of the lower end of the casing.

As shown in the drawings, the table-gear 9 is preferably located below the level of the 30 derrick-floor 2. This arrangement avoids the necessity of removing said gear when using the standard outfit and enables the operator to keep the casing rotating while drilling with the standard tools, preventing the 35 casing from freezing during the operation of the standard tools.

In drilling through soft formations or such as are intermingled with shale or lime shells, the apparatus is converted into the 40 rotary form, while upon encountering hard rock formations the standard equipment is employed, the change from one to the other being made in a comparatively short time. In drilling through hard formations with 45 the reciprocating or cable tools, the rotary feature of the casing affords the important advantage that the hole drilled by such tools may be enlarged or under-reamed by the shoe 24 to the external diameter of the casing 50 by rotating the casing, thereby permitting the latter to be sunk to the bottom of the hole drilled by the cable tools.

As before stated, this improved method 55 and apparatus permit the use of a casing of uniform diameter throughout its depth and constructed of medium sized pipe, such as eight-inch, instead of requiring numerous strings or sections of progressively smaller diameter. This results in an important saving 60 in the cost of pipe, and also in tools, as only one full set of a single size is required, instead of numerous different-sized sets for the different-sized pipes ordinarily used. Furthermore, the coupling and uncoupling 65 of the pipe-sections forming the ordinary

rotary drill stem require considerable time, and as the present apparatus does away with that stem, it saves not only that item of labor but also the cost of the large amount of pipe required for the different-sized drill-stems, as well as the transportation charges and duty on the same. Compared with the ordinary standard outfit, this improved apparatus saves more than seventy per cent. of the casing-pipe and fifty per cent. of the 70 labor, and compared with the ordinary rotary outfit, it saves more than sixty per cent. of the casing-pipe and seventy per cent. of the labor. With this improved outfit, the bits can moreover, be changed in from ten 80 to thirty minutes, according to the depth, whereas with the rotary outfits now in use, such change requires from one hour to one day. This apparatus has the further advantage that when the well is finished, the casing is already set, thus saving from a day to a week over the ordinary rotary methods in use, which require the well to be washed out and reamed down to set the casing. The casing can also be more reliably cemented in 85 the lime or oil-sand, as the drilling can be continued with the shoe in the lime, and on account of its perforated and upwardly-tapering construction, the shoe can be fastened in the lime as securely as the lime itself. Furthermore, the annoyance of mud blow outs from gas is avoided, as the casing is carried down as fast as it drills its hole and the mud is promptly piped off. Again, 90 with this outfit, the casing may be kept rotating in the mud while changing bits, avoiding all danger of freezing up while making the change. As regards fishing for 95 tools, there is also an important saving over ordinary outfits, as a fishing job is never in the mud but always inside of the casing. The draining of the hydraulic jacks can be 100 regulated to feed the rotary casing a small fraction of an inch at a time, thus effectually guarding against twisting off the casing 110 which practically forms the stem of the drilling tool.

It is obvious that the apparatus may be modified in various respects within the scope of the appended claims, and I do not therefore wish to be limited to the particular construction herein shown and described.

I prefer to employ in connection with this well drilling apparatus, the collapsible rotary under-reamer bit and the horn socket 120 shown and described in separate applications for patent filed by me on the 15th day of February, 1915, Serial No. 8326 and No. 8327, respectively, but other suitable rotary tools and any other suitable horn socket 125 may be used, if desired.

I claim as my invention:

1. The herein described method of drilling wells, which consists in sinking a casing into the well-hole, lowering a drilling bit 130

- through the casing and reciprocating the same by a cable and cable tools, and at the same time rotating the casing to prevent freezing thereof during said drilling operation.
2. The herein described method of drilling a well, which consists in sinking into the well a casing provided with a shoe, drilling hard formations by lowering a cable and cable tools through said casing and reciprocating the same therein, and then rotating the casing and shoe to underream the well-hole and allow the casing to be sunk to the bottom of the hole drilled by said cable tools.
3. A combined rotary and reciprocating drilling apparatus for oil wells, comprising a casing arranged in the well, means for rotating the casing, a stemless rotary drilling tool, means for coupling said tool to the casing to turn therewith, said casing having a sufficient internal diameter throughout its depth to permit the tools and drill-bit of a reciprocating outfit to be lowered therethrough.
4. In a well drilling apparatus, the combination of a casing arranged in the well, means for rotating said casing, a seamless drilling tool, and means remote from the lower end of the casing for coupling said tool to the casing to turn therewith.
5. In an apparatus for drilling oil wells, the combination of a casing arranged in the well and having an internal stop, means for rotating said casing, a tool-socket having a retractable member adapted to engage said stop when projected, and means carried by the tool socket and separate from said retractable member for coupling the tool socket to the rotary casing.
6. In an apparatus for drilling oil wells, the combination of a casing arranged in the well and having an internal stop, means for rotating said casing, a tool-socket having outwardly-swinging dogs arranged to engage said stop, a spring for projecting said dogs, and means carried by the tool socket for coupling the same to the rotary casing.
7. In an apparatus for drilling oil wells, the combination of a rotatable casing arranged in the well and provided with an internal stop and above said stop with coupling means, means for rotating said casing, and a tool-socket provided with a retractable stop-member adapted to engage said stop when projected and above said member with coupling means adapted to engage with the first-named coupling means, said internal stop having means for automatically turning the tool-socket in the casing to bring the coupling means of the casing and the tool-socket into proper mesh.
8. In an apparatus for drilling oil wells, the combination of a rotatable casing arranged in the well and provided with an internal stop having V-shaped teeth and above said teeth with coupling-ribs, means for rotating said casing, and a tool-socket provided with toothed outwardly-movable dogs adapted to engage said toothed stop and above said dogs with toothed clutch blocks coöperating with said coupling ribs.
9. In an apparatus for drilling oil wells, the combination of a casing arranged in the well and provided with an internal stop and above said stop with a clutch member, means for rotating said casing, and a tool socket having a retractable member coöperating with said stop and a clutch-member coöperating with the first-named clutch-member to drive the tool-socket from the casing.
10. In an apparatus for drilling oil wells, the combination of a casing arranged in the well and provided with an internal stop-shoulder and above said shoulder with longitudinal clutch-ribs, means for rotating said casing, and a tool-socket having retractable dogs arranged to engage said shoulder when projected, clutch-blocks arranged to engage said clutch-ribs and a wedge interposed between said blocks.
11. In a well-drilling apparatus, a tool socket having outwardly-swinging stop-dogs, a cam-bar slidable vertically in the body of the socket and bearing against the upper ends of said dogs, and a spring for depressing said cam-bar.
12. In a well-drilling apparatus, a tool socket having outwardly-swinging stop-dogs, a cam-bar slidable vertically in the body of the socket and bearing against the upper ends of said dogs, a rod engaging said cam-bar and arranged to slide lengthwise of the tool-socket, said rod carrying a projection, and a spring applied to said rod and bearing at one end against said projection and at its other end against the body of the tool socket.
13. In a well-drilling apparatus, a coupling sleeve adapted to form a section of the well-casing and having an internal stop arranged to be engaged by a corresponding member of a tool-socket and a clutch-member separate from and above said stop arranged to be engaged by a coöperating member of the tool-socket.
14. In a well-drilling apparatus, a coupling sleeve adapted to form a section of the well-casing and provided with an internal toothed stop-shoulder and above said shoulder with internal longitudinal clutch-ribs.
15. In a well-drilling apparatus, a tool-socket having a descending water passage extending inwardly from its periphery and thence downwardly through its central portion, an ascending relief-passage extending upwardly from its lower end, and an upwardly-opening check-valve applied to said relief-passage.

16. In a well-drilling apparatus, the combination of the derrick-floor, a hydraulic jack having its cylinders arranged below said floor, and a supporting-plate mounted on said jack and adapted to carry the well-casing.

17. In a well-drilling apparatus, the combination of a supporting plate, means for raising and lowering said plate, and anti-friction bearing resting on said plate, and an elevator supported on said bearing and adapted to carry a rotary well-casing.

18. In a well-drilling apparatus, the com-

bination of a supporting plate, means for raising and lowering said plate, an anti-friction bearing resting on said plate, a well-casing passing through said plate and said bearing, an elevator mounted on said bearing and applied to said casing, and a flush head attached to the upper end of the casing.

Witness my hand this 6th day of February, 1915.

ELMER E. SHAFFER.

Witnesses:

CHAS. F. BISSETT,

W. H. MANDEVILLE.

Copies of this patent may be obtained for five cents each, by addressing the "Commissioner of Patents, Washington, D. C."

It is hereby certified that in Letters Patent No. 1,166,011, granted December 28, 1915, upon the application of Elmer E. Shaffer, of Tulsa, Oklahoma, for an improvement in "Methods and Apparatus for Drilling Oil and Gas Wells," an error appears in the printed specification requiring correction as follows: Page 6, line 27, claim 4, for the word "seamless" read *stemless*; and that the said Letters Patent should be read with this correction therein that the same may conform to the record of the case in the Patent Office.

Signed and sealed this 18th day of January, A. D., 1916.

[SEAL.]

J. T. NEWTON,

Acting Commissioner of Patents.

Cl. 255—3.
